(57) **CLAIM**

The ornamental design for a cook tool as shown and described.

DESCRIPTION

FIG. 1 is a perspective view of a cook tool showing our new design;

FIG. 2 is a front view thereof;

FIG. 3 is a back view thereof;

FIG. 4 is a right view thereof;

FIG. 5 is a left view thereof;

FIG. 6 is a bottom view thereof; and,

FIG. 7 is a top view thereof.

The broken lines are used to show portions of the cook tool that are not being claimed, and thus form no part of the claimed design.

The stippling shown in the figures depicts a contrast in appearance.
